UNITED STATES PATENT OFFICE.

ELISIARIO CASTANHO, OF SAO PAULO, BRAZIL.

RAILWAY SYSTEM.

1,112,979.

Specification of Letters Patent.

Patented Oct. 6, 1914.

Application filed October 29, 1913. Serial No. 798,001.

To all whom it may concern:

Be it known that I, ELISIARIO CASTANHO, a citizen of Brazil, and a resident of the city of Sao Paulo, State of Sao Paulo, Brazil, have invented a new and Improved Railway System, of which the following is a full, clear, and exact description.

My invention relates to a railway system which may be embodied in the form of amusement apparatus, or in a railway for general purposes.

It is a design of my invention to provide a railway car and tracks constructed and arranged to promote safety in guarding against derailment of the car.

It is a further design of my invention to provide a novel arrangement of track brakes on the car.

Other objects will appear from the following description.

Reference is to be had to the accompanying drawings forming a part of this specification, in which similar characters of reference indicate corresponding parts in all the views.

Figure 1 is a side elevation of a car embodying my invention, the view showing also a section of elevated track for the car; Fig. 2 is a central longitudinal vertical section; Fig. 3 is a sectional plan view; Fig. 4 is a rear end view with parts broken away, the view showing ground tracks in addition to elevated tracks; Fig. 5 is a detail end view on one of the brakes employed on my improved car; Fig. 6 is a sectional plan view of said brake on the line 6-6 of Fig. 5; Fig. 7 is a detail end view of another of the brakes; Fig. 8 is a side elevation showing the overlapping elevated and ground tracks; Fig. 9 is a cross sectional view indicating a modified arrangement of the tracks; and Fig. 10 is a view similar to Fig. 9 and showing another arrangement of the tracks.

In constructing a car in accordance with my invention the body 10 is, at the ends, preferably tapered, presenting curvilinear angles. The car is provided with any suitable motor 11, which in practice may be in driving connection with any approved means for propelling the car, there being indicated in the present example a front propeller 12, the shaft 13 of which may be driven by an endless chain 14 having suitable driving connection with the motor 11.

A framework is provided which, for economy and lightness while affording the de-

sired strength, is preferably made up of tubular elements or pipe sections, it being understood that the frame will be varied in practice, according to the design of the car. 60 In the present example the frame comprises a central longitudinal top bar 15, a similar longitudinal bottom bar 16, a vertical connecting bar 17 at the rear angle of the car, and front upright bars 18, which at their lower ends are of the general form of a fork, 65 the upper ends of which are united to the vertical member 18^a. At the front the vertical bars 17 may be braced by diagonal members 19. In connection with the head frame members, side frames are provided, 70 each comprising a longitudinal top bar 20, a longitudinal bottom bar 21, and upright bars 22 connected at the lower ends with the bars 21 and joined at their upper ends 75 to the main longitudinal bar 15 by transverse members 22^a. The lower bars 21 of the side frames are joined by cross bars 21^a (Fig. 4).

Mounted in the side frames are upper 80 vertical running wheels 23 and lower vertical running wheels 24, spaced vertically to receive between them the elevated track rails 25, which are of the bull head type, presenting upper and lower heads forming treads 85 for the respective wheels 23, 24. In connection with the elevated tracks 25 ground tracks 26 are employed, as hereinafter further explained.

At the front and back at the sides of the 90 car, auxiliary frame members 27 are connected with the upright members 22 of the side frames and braced by any suitable frame members 28. The auxiliary frames 27 are provided at their ends with brackets 95 29, formed on or secured to which are pairs of hooks 30, the hooks of a pair being approximately in vertical alinement and extending laterally above and below the tracks 25, the hooked ends being disposed toward 100 each other and lying outside the heads of the rails. The said hooks serve to prevent derailment by engaging the track in the event the gage of the latter should be slightly broadened at any given point along the 105 track. The brackets 29 or any other convenient supporting members of the frame mount horizontal friction wheels 31, disposed at the inner sides of the rails and adapted to contact with the latter when the 110 car rounds a curve. The said wheels 31 serve as pilot wheels and relieve the pressure

and strain on the flanges of the running wheels 23, 24 on curves. The friction wheels 31 may be adjusted laterally with respect to the rails 25, there being provided for the 5 purpose slots 32 in the brackets 29, in which the pivot pins 33 of said wheels may be moved.

Additional frame members 34 extend from the transverse frame members 28 or other 10 convenient frame elements and are connected by the cross bars 35, 35^a. These last mentioned frame members support brake devices which preferably comprise at one end, say the back, roller brake devices adapted to 15 engage the track, and at the opposite end, brake shoes instead of rollers. The frame members 34, 35, 35^a support bearing members 36, 36^a, in which upright shafts 37, 37^a have bearings, said shafts being provided 20 with sprocket wheels 38 driven by endless chains 39, 39^a, which are driven from the motor 11, and controlled in any suitable manner by the motorman. As here shown the chain 39, passes around guide sprockets 25 39^b, and longitudinally around a driving sprocket 39^c, (Fig. 3). Similarly the chain 39^a passes around guide sprockets 39^d and longitudinally around a drive sprocket 39^e. The shafts of the sprockets 39^c, 39^e, have 30 hand wheels 39^f or other means to enable the motorman to apply or release the brakes through the medium of the chains 39, 39^a.

The roller brakes are designated generally by the numeral 40 and the shoe brakes by 35 the numeral 41, and are shown in detail in Figs. 5, 6 and 7. The brakes 40 comprise a brake block 42, in which is journaled the upper brake roller 43 and a lower brake block 44, in which is journaled a pair of 40 lower brake rollers 45, the upper roller being adapted to bear against the top of the track 25 and the rollers 45 against the under side of the rail. Similarly the upper brake block 42^a of the shoe brake 41 carries an integral brake shoe 43^a, and the lower brake block 44^a is formed with a pair of rigid brake shoes 45^a. Both shafts 37, 37^a, have right and left threads 46, 47 engaging corresponding threads in the respective brake 45 blocks, so that the turning of the said shafts in their bearings 36 through the medium of the sprocket wheels 38 and chains 39, 39^a, will serve to move the brake rollers and 50 brake shoes against the rail 25, or away from the rail to apply or release the brakes. By providing the roller brakes at one end of the car the braking action thereof will be gradual, and the shoe brakes can then be applied to give a more positive braking action, the 55 successive use of the brakes thus serving to prevent a jar.

The overhead track may be supported and braced in any suitable manner. As here shown the rails 25 are carried by blocks 49 60 on posts 50 that rise from the cross ties 51

diagonal braces 52 being employed at the outside of the posts. In the form shown in Fig. 9, uprights 52 rise from the ties 51^b and are joined by an overhead cross bar 53, the elements 52, 53, being preferably in the form 70 of a single arch. The lower running wheels 24 in this form of the invention run on ground tracks 26, while the upper wheels 23 travel along the under side of overhead rails 54 depending from the cross bars 53. Horizontally disposed friction wheels 55 corresponding with the friction wheels 31, travel along the inner sides of side rails 56 on the uprights 52.

In the form shown in Fig. 10, the uprights 52^a and the cross bar 53^a are supported from the ties 51^b, and a central mono-rail 56 is supported at the under side of the cross bar 53, it being understood that said cross bars are arranged at proper intervals throughout the length of the track. The lower running wheels of the car run on the tracks 26 as in the form shown in Fig. 9, and instead of the upper running wheels, a single friction wheel 23^a may run along 80 the underside of the mono rail, while horizontal guard wheels 55^a engage the said rail at each side. In all the forms of the invention it will thus be seen that the arrangement of the tracks and wheels prevents 85 derailment of the car.

Referring particularly to Fig. 8, it will be seen that a terminal of the overhead track 25 extends beyond and above the adjacent end of the terminal of the ground track 100 26 and the arrangement is such that the car will leave the overhead tracks and take the ground tracks without shock or jar. The end of each rail of the overhead track 25 is given a slight downward inclination as at 105 25^a, and the lower head 25^b gradually tapers and terminates short of the end of the rail, so that the under wheels 24 will gradually leave the underside of the overhead track, and as gradually engage the ground 110 tracks 26. Similarly the downward inclination of the overhead tracks will result in the weight of the car gradually leaving the overhead tracks, since the lower running wheels 24 will engage the ground tracks 115 26 as the upper wheels 23 leave the overhead tracks 25^a.

It is to be understood that the arrangement of seats, windows, etc., in the car as illustrated, may be greatly varied in practice. The type of car shown is conveniently provided with side doors 10^a, arranged between the respective pairs of upper and lower running wheels.

Where an internal combustion motor is 120 employed, the motor may be air cooled by any approved construction of cooler adapted for the purpose, the air to be taken through suitable hooded openings 10^b.

In practice, when a propeller is used, a 130

suitable clutch 57 and clutch lever 58 are employed, as indicated in Fig. 2, for making and breaking the driving connection with the chain 14. Thus, if the propeller is disconnected and free to revolve loosely, it serves as a retarder in arresting the motion of the car.

Having thus described my invention, I claim as new, and desire to secure by Letters Patent:

1. A railway, comprising an overhead track, a lower track below and in approximate vertical alinement with the overhead track, said overhead and lower tracks overlapping each other, and a car having upper and lower running wheels approximately in vertical alinement and spaced to run respectively on the top and below the overhead track, the overhead track having at the overlapping end a downward inclination in the direction of the lower track.

2. A railway, comprising an overhead track having treads at the top and bottom, a lower track below the overhead track, said tracks overlapping each other, and a car having upper and lower running wheels spaced to run respectively on the upper and lower sides of the overhead track, the overhead track at the overlapping end being inclined downwardly in the direction of the lower track and having the head at the under side thereof gradually diminishing at the incline.

3. A railway car having upper and lower running wheels vertically spaced to accom-

modate a track rail therebetween, a horizontal wheel on the car inside the plane of the treads of the wheels to bear upon a track rail, at the inside thereof in rounding a curve, and laterally disposed hooked members extending outwardly to engage a track rail at the outside.

4. A railway car having upper and lower running wheels spaced from each other and in vertical alinement to accommodate a track rail therebetween, and hooked members extending outwardly and spaced to accommodate a track rail between them.

5. A car comprising a body having tapered ends, frame members extending longitudinally of the car at the top and bottom, members connecting the top and bottom frame members; side frames having connection with the top and bottom frame members, and running wheels mounted on said side frames.

6. A car comprising a frame having connected top and bottom members arranged approximately centrally of the car, side members connected with the top and bottom members, a car body mounted within the frame, and running wheels on the side frames.

In testimony whereof I have signed my name to this specification in the presence of two subscribing witnesses.

ELISIARIO CASTANHO.
